UNITED STATES PATENT OFFICE.

FRANK V. CARMAN, OF OAKLAND, CALIFORNIA.

SPIKE-HOLE-PLUG MACHINE.

1,218,836.

Specification of Letters Patent. Patented Mar. 13, 1917.

Application filed June 7, 1916. Serial No. 102,236.

To all whom it may concern:

Be it known that I, FRANK V. CARMAN, a citizen of the United States, residing at Oakland, in the county of Alameda and State of California, have invented certain new and useful Improvements in Spike-Hole-Plug Machines, of which the following is a specification.

My invention relates to wood-working machines in general, and particularly to that class of machines adapted for making plugs to fill the spike-holes left in railway cross-ties, after the spikes as originally driven to hold the rails are, for any reason, drawn out, the purpose of the filling being to restore the holding capacity of the ties for fresh spikes or the old ones redriven.

The object of my invention is to provide a machine adapted for the rapid and accurate cutting and pointing of groups or clusters of plugs in the ends of blocks of wood, and then dismembering the groups into individual plugs.

To this end my invention consists in the novel machine which I shall hereinafter fully describe by reference to the accompanying drawings, wherein—

Figure 1 is a side elevation of my machine.

Fig. 2 is a plan of the same.

Fig. 3 is a vertical cross section of the machine on the line 3—3 of Fig. 2, certain parts being omitted for the sake of clearness.

Fig. 4 is an elevation of the work-table, one of the cradles thereon being shown in its two positions of functional relation to the saw-gang, one position being in dotted lines.

Fig. 5 is a broken plan view of the work-table, showing three of its swinging cradles.

Fig. 6 is a section enlarged on the line 6—6 of Fig. 5, of one of the cradles.

Fig. 7 is a perspective view broken, of the end of one of the blocks showing the formation in its end of a group or cluster of the spike-hole plugs prior to dismemberment.

Fig. 8 is an end elevation of the saw-gang showing the staggered relation of the teeth of the saws.

Fig. 9 is a front elevation of the saw-gang.

Fig. 10 is an end-view partly in section of the pointing-knife head.

Fig. 11 is a view with parts in section and taken on line 11 of Fig. 10.

Figs. 12, 13 and 14 are detail view of the sliding boxes of the belt tightener.

1 is the main frame of the machine. At the head of the frame is the work-table 2 of the turn-table type with its axis at 3 and mounted upon a fixed base 4 with rollers 5, as seen in Fig. 1. Upon the table 2 are the block-holders or cradles 6. These may be in any number, four being here shown, for example. Each cradle is a two-sided opening-ended angular structure, and is hinged to the table at 7 along the line of its angle, so that it may be turned through an arc of 45 degrees, its sides resting alternately upon the table surface. These two positions are best seen in Fig. 4. The cradles are radially disposed upon the table and at their outer ends segmental pieces 8, fixed to the table, fill in the table arc and serve as supports for the projecting ends of the blocks 9 from which the plugs are to be made. The blocks 9 lie in the angles of the cradles 6, as seen in Fig. 6, their outer ends projecting therefrom and upon the segmental pieces 8, as in Fig. 5, the extent of the projection of the blocks beyond said cradles and places being determined by the length of the plugs to be made. The blocks 9 may be of any shape in cross section. For illustration, I have shown the block in one instance in Fig. 1 as round, while in Figs. 4, 5 and 6 I show the block square. They are firmly held in the cradles, by any suitable means. In the present illustration I have shown the clamping means as comprising a cross stirrup 10 and a handled screw 11 threaded through the stirrup, its inner end being adapted to engage the block, as seen in Fig. 6, with a pressure sufficient to hold it in its seat and to relieve it again. There may be one or more of these clamping devices upon each cradle. For illustration merely, I herein show but one on each cradle, located near its outer end, so that it will firmly hold the block near its projecting end, at which portion said block during operation receives the strain of the cutting devices.

Hinged at 12 near the foot of the main frame 1 is the cutter-carrying frame 13 which is adapted to move down and up in a vertical arc, about its hinges 12 as an axis. At the forward or free end of the swinging frame 13 is carried the gang of spaced saws 14, and above the saw-gang, said frame carries the pointing-knives 15. The position of the saw-gang and the pointing-knives is such that as the frame 13 which carries them swings down they will act upon the projecting end of the block 9 to cut therein

100

105

110

the kerfs which define the plugs, and to bevel or point the ends of said plugs.

Mounted upon the main frame 1 beside and close to the periphery of the turn-table 2, at about 90 degrees removed from the saw-gang and pointing-knives, is the cut-off saw 16. The face of this saw next to the table is smooth and unobstructed, as seen in Fig. 2, and the position of the saw is such 10 as to act upon the projecting end of the block 9 at the base of the kerfs made by the saw-gang 14, thereby dismembering the groups or clusters of plugs previously made.

Before continuing the description of the 15 machine, it will be well, at this point, to set forth its general operation, after which details of construction and arrangement will be better understood, both as to their nature and objects.

20 Let it be supposed, to begin with, that the swinging frame 13 is raised to its upper limit, so that both the pointing-knives 15 and the saw-gang 14 lie well above the level of the turn-table 2, as seen in Fig. 1. The 25 operator standing by the side of the table remote from the cut-off saw 16, now places a block 9 in a cradle 6, said cradle being at the time in its first position, that is with its open side facing him. In the cradle he

30 clamps the block firmly, by means of the screw 11, the end of the block projecting the required distance to make the predetermined length of plugs. The block being thus clamped and its projecting end further

35 supported upon the filling piece 8 is now ready to be operated upon. The operator then swings the turn-table through an arc sufficient to carry the projecting block into the path of the cutting devices and there

40 stops it. This is the position shown by the full lines in Fig. 4. The swinging frame 13 now moves down and the saws of the gang 14 in passing the block end make a number of parallel kerfs therein to the depth predetermined, that is, the length of the plugs to

45 be made. The pointing-knives 15 following the saw-gang, bevel off the saw-cut sections on two sides. After the cutting devices have thus acted upon and passed the block,

50 the swinging frame 13 moves up again to its first position, the cutting devices returning through the cut block end. Then the operator swings the cradle 6 over to its second position, shown by the dotted lines in

55 Fig. 4, thereby turning the block it contains a quarter round, the turn-table 2 being still stationary. Now, the swinging frame 13 moves down once more, and this time the saws 14 cut kerfs in the block at

60 right angles to the first kerfs, and the pointing knives 15 bevel off the other two sides of the plug ends. There is now cut in the end of the block a number of square and pointed plugs, which as yet are not severed from the block but remain as a group or

cluster, as seen in Fig. 7. Thereupon the operator swings the turn-table 2 further in its circular path, and the cutting devices return to their elevated position. When the block reaches the cut-off saw 16 and moves by it, said saw cuts off the plugs, thereby dismembering the group or cluster; and the separated plugs drop down and are ready for sacking. Meanwhile a repetition of the operation is taking place with another block and so on; and each block is successively adjusted in its cradle until it is used up; and then a new block is put in the cradle.

It is to be noted that on account of the 80 different position in space which the block 9 occupies in its first and second positions, due to the swinging of its cradle on the line of its angle, it is necessary that the length of the saw-gang 14 and the pointing knives 85 15 be sufficient to include the combined width of both positions, in order to meet the block squarely in both positions. Accordingly, it will be seen in Figs. 2 and 4, and particularly the latter, that the saw-gang 90 has a length more than double the width of the block; and this is true also of the series of pointing-knives. Therefore, in the first position of the block the first half of the cutting devices come into operation, and in the second position the other half are used, as will readily be seen by reference to Fig. 4.

The saws of the gang 14 may be of any approved type, preferably with inserted 100 teeth, as shown in Fig. 8. The saws are provided with spacing collars 17 riveted to them and these collars are grooved at 18 to fit a feather 19 on the mandrel 20.

A feature to be noted is that the grooves 105 18 in the eyes of the saws are differently located with respect to the circumference in order to throw the teeth of the saws out of line, that is, to stagger them as seen in Fig. 8. This is of advantage in a saw-gang as 110 applied to work of the nature herein described, which requires the saws to be near together and to operate upon a relatively small surface, as it prevents too great simultaneous impact pressure.

115 The pointing knife device or head may be of any suitable character, for example, as shown in Figs. 10 and 11, wherein the general type of planer heads is followed. 21 is the mandrel and 22 is the head. The 120 four sides of the head are provided with a T-groove 23, and the surface of each side is recessed to receive the pointing-cutting blades 15 which lie therein and are clamped by bolts 24.

125 Power is led into the machine through the pulley 25 on the drying shaft 26 mounted upon the foot of main frame 1.

Upon the shaft 26 are two pulleys 27, (Fig. 2) from each of which a belt 28 passes 130

to a pulley 29 on each end of the mandrel 21 of the pointing knives 15; thence back to a tightener pulley 30 on each end of a counter shaft 31; thence forward to a pulley 32 on each end of the mandrel 20 of the saw-gang 14, and thence back to the pulleys 27 on the driving shaft. The counter shaft 31 of the tightener pulleys 30 is mounted in boxes 33 adapted to slide on tracks 34 on the main frame 1. Lines 35 carrying suspended weights 36 are secured to the slidable boxes 33 and thus tension is kept on the belts 28.

By this mechanism the pointing-knives 15 and the saw-gang 14 are driven. Upon the driving-shaft 26 is a pulley 37 from which a crossed-belt 38 extends to a pulley 39 on the shaft 40 of the cut-off saw 16, whereby said saw is driven.

The swinging frame 13 which carries the saw-gang 14 and the pointing knives 15 is operated by the following connections. On the top of an uprising portion 1' of the main frame 1 is mounted a shaft 41 upon which is a sprocket 42. In the base of the frame portion 1' is mounted a shaft 43 which carries a sprocket 44. Between these sprockets 42 and 44 extends an endless chain 45, and said chain at a point intermediate the sprockets is fastened to a cross-bar 13' of the swinging frame 13. It will now be seen that a reciprocal movement of the chain 45 will lower and raise the swinging frame 13. This movement of the chain is imparted to it by means of a sprocket 46 on the end of the upper shaft 41, from which sprocket a chain 47, as seen in Fig. 1, passes down to a sprocket 48 on a short counter shaft 49 mounted in the frame. This shaft may be operated either by hand, as is indicated by the crank 50, or by power, by the following means, as best shown in Fig. 2. Upon the counter shaft 49 is mounted a fast pulley 51. On the shaft, inside this fast pulley is a loose pulley 52 and on said shaft outside said fast pulley is another loose pulley 53. From the inside loose pulley 52 a crossed-belt 54 leads to a pulley 55 on the driving shaft 26, and from the outside loose pulley 53 a straight belt 56 leads to the pulley 55 on the driving shaft. A shifting lever 57, as seen in Fig. 3, acts on the crossed-belt 54 to throw it to and from the fast pulley 51, and another shifting lever 58 acts similarly on the straight belt 56.

In order to counterbalance the swinging frame 13, so that its operation will be easy, there is a weight 59, as seen in Fig. 1, suspended from a chain 60 which passes over a sprocket 61 mounted in the top of the frame portion 1', and down to a cross-bar 62 of the swinging frame 13.

In order to facilitate the handling of the blocks 9 in lifting them and placing them in the cradles, there is a hoisting derrick or crane comprising a mast 63 pivotally mount-

ed above and below in extensions 64 of the main frame 1, so that said mast may turn on its axis. The mast carries a boom 65 from which is properly suspended suitable gripping dogs 66, carried by a running line 67 operated by a winch 68 carried by the mast, as seen in Fig. 1.

I claim:—

1. In a plug forming machine of the character described, the combination with a reciprocating frame, of cutting instrumentalities carried by said frame and movable therewith, a work-table movable in a plane perpendicular to the movement of the reciprocating frame, means on the work-table for supporting a plug-block and permitting the same to occupy successively different positions to the action of the cutting instrumentalities for cutting intersecting kerfs in said block to produce a multitude of block-like end sections, substantially as described.

2. In a machine for forming a multitude of block-like end sections upon a plug-block, the combination with a vertically swinging frame, cutting instrumentalities carried by said frame and movable therewith, a horizontally disposed work-table movable in a circular course, means on said table for supporting a plug-block and permitting the same to occupy different positions relative to the cutting instrumentalities for forming in said block a plurality of intersecting kerfs to produce block-like end sections.

3. In a machine of the class described, the combination with a reciprocating frame, means for supporting the same, cutting instrumentalities carried by said frame and movable therewith, a work-table, means on said table for supporting a plug-block and permitting the same to be presented in successive positions to the action of the cutting instrumentalities upon the raising and lowering of the reciprocating frame to form within said plug-block a plurality of intersecting kerfs producing a multitude of block-like sections, substantially as described.

4. A machine for the described purpose, comprising a vertically swinging frame; plug-cutting instrumentalities carried by said frame; a horizontally turnable work-table movable in a plane perpendicular to the plane of the reciprocating path of the swinging frame; and means on the table by which the plug-block may be presented to the action of the cutting instrumentalities, in two successive positions, at right angles to each other.

5. In a machine of the class described, the combination with cutting instrumentalities, means for movably supporting said instrumentalities, of a work-table, a cradle on said table for receiving a plug-block and composed of two sides disposed at right angles to each other, means for supporting the table for a movement, the said cradle being

adapted for a movement through a quarter turn to present the plug-block to the action of the cutting instrumentalities in two successive positions for forming in the block a series of intersecting kerfs producing block-like end sections.

6. A machine for the described purpose, comprising a reciprocative frame; instrumentalities for cutting a series of kerfs carried by the frame; a work-table movable in a plane perpendicular to the plane of the reciprocative path of the cutting instrumentalities; and a plug-block-holding cradle on said table, movable about an axis adapting it to present the plug-block in two successive positions at right angles to each other, to the action of the cutting instrumentalities.

7. A machine for the described purpose, comprising a reciprocative frame; instrumentalities for cutting a series of kerfs carried by the frame; a work-table movable in a plane perpendicular to the plane of the reciprocative path of the cutting instrumentalities; a plug-block-holding cradle on said table composed of two sides at an angle; and a hinge connection between the table and cradle in the line of the cradle angle, adapting it for movement through a quarter turn to present the plug-block to the action of the cutting instrumentalities in two successive positions at right angles to each other.

8. A machine for the described purpose, comprising a reciprocative frame; instrumentalities for cutting a series of kerfs carried by the frame; a work-table movable in a plane perpendicular to the plane of the reciprocative path of the cutting instrumentalities; a plug-block-holding cradle on said table composed of two sides at an angle; a clamping device carried by the cradle for holding the plug-block in its angle; and a hinge connection between the table and cradle in the line of the cradle angle, adapting it for movement through a quarter turn to present the plug-block to the action of the cutting instrumentalities in two successive positions at right angles to each other.

9. A machine for the described purpose, comprising a reciprocative frame; a gang of spaced saws carried by the frame; a gang of spaced pointing-knives carried by the frame behind the saw-gang; a work-table movable in a plane perpendicular to the plane of the reciprocative path of the saws and knives; and a plug-block holding cradle on the table, movable about an axis adapting it to present the plug-block in two successive posi-

tions at right angles to each other, to the action of the saws and knives.

10. A machine for the described purpose, comprising a reciprocative frame; a gang of spaced saws carried by the frame; a gang of spaced pointing-knives carried by the frame behind the saw-gang; a work-table movable in a plane perpendicular to the plane of the reciprocative path of the saws and knives; a plug-block holding cradle on said table composed of two sides at an angle; and a hinge connection between the table and cradle in the line of the cradle angle, adapting it for movement through a quarter turn to present the plug-block in two successive positions at right angles to each other, to the action of the saws and knives.

11. A machine of the character described comprising movable cutting instrumentalities, plug supporting means for presenting a plug in the path of said movable cutting instrumentalities, said supporting means permitting the plug to occupy positions at right angles to each other to present different faces to the cutter, said cutters forming in the block a multitude of closely associated intersecting kerfs extending entirely therethrough to produce pointed block-like end sections, substantially as described.

12. In a machine of the character described, the combination with swinging cutting instrumentalities, plug block supporting means for presenting a plug block in the path of said cutting instrumentalities, said supporting means permitting the instrumentalities to engage different portions of the plug block to form therein a series of intersecting kerfs producing block-like end sections, for the purpose described.

13. In a machine of the character described, the combination with movable cutting instrumentalities, plug block supporting means for presenting a plug block in the path of said cutting instrumentalities, said supporting means permitting the instrumentalities to engage different portions of the plug block to form therein a series of intersecting kerfs producing block-like end sections, and means for raising and lowering said movable cutting instrumentalities.

In testimony whereof I have signed my name to this specification in the presence of two subscribing witnesses.

FRANK V. CARMAN.
